United States Patent

Des. 234,936
Patented Apr. 22, 1975

234,936

COFFEE TABLE

Gary J. George, 5174 Library Road,
Bethel Park, Pa. 15102

Filed May 14, 1973, Ser. No. 359,666

Term of patent 7 years

Int. Cl. D6—03

U.S. Cl. D6—177

FIG. 1.

FIG. 2.

FIG. 3.

FIG. 4.

FIG. 1 is a top perspective view of the coffee table, showing my new design;

FIG. 2 is a top plan view of FIG. 1;

FIG. 3 is a side elevational view and the opposite side thereof is a mirror image of this view;

FIG. 4 is an end elevational view, the opposite end being identical thereto.

I claim:

The ornamental design for a coffee table, as shown and described.
